LAUNDRY MACHINE

Ray C. Sandin, Oak Park, and Thomas M. Steinbach, Chicago, Ill., assignors to Hotpoint Inc., a corporation of New York

Application April 21, 1950, Serial No. 9,413

Term of patent 14 years

(Cl. D49—2)

To all whom it may concern:

Be it known that we, Ray C. Sandin, a citizen of the United States, residing at Oak Park, in the county of Cook and State of Illinois, and Thomas M. Steinbach, a citizen of the United States, residing at Chicago, in the county of Cook and the State of Illinois, have invented a new, original, and ornamental Design for a Laundry Machine, of which the following is a specification, reference being had to the accompanying drawing, forming a part thereof.

In the drawing, Figure 1 is a front perspective view of a laundry machine showing our new design; and

Fig. 2 is a reduced side view thereof.

We claim:

The ornamental design for a laundry machine, substantially as shown.

RAY C. SANDIN.
THOMAS M. STEINBACH.
